UNITED STATES PATENT OFFICE

2,064,662

X-RAY DEVICE

Walter Hofmann, Rudolstadt in Thuringia, Germany, assignor to General Electric Company, a corporation of New York

Application February 16, 1929, Serial No. 340,536
In Germany February 24, 1928

3 Claims. (Cl. 250—35)

In X-ray tubes known up to the present time equipped with devices protecting against undesired passing of X-rays towards the outside, disturbances occur when they are operated with high electric voltages. These disturbances are frequently caused by auto-electronic discharges due to the fact that inside the evacuated container relatively large metallic bodies which have a high potential difference, are mounted close to each other.

According to the invention these mentioned disturbances are eliminated—for extensive protection against undesired passing of X-rays towards the outside—by the anti-cathode being installed in a chamber which is opaque to X-rays with the exception of a window through which the X-rays to be used traverse. This chamber is provided with a small window to allow the cathode ray bundle to enter, the latter therefore being located remote from the anti-cathode at a place which is nearest to its cathode.

Other objects and features will be apparent as the specification is perused in connection with the accompanying drawing in which Figs. 1, 2 and 3 represent exemplary embodiments of the invention.

Referring to the drawing, the metal ring 1 is fused with the short inside wall 2 (Fig. 1) of the tubular almost cylindrical hollow glass body 3. This ring 1 is welded to the pipe 4 which is to be constructed with double walls, in order to provide an opportunity for cooling with liquids, and which is conducting and to be most advantageously made of iron for the sake of easier evacuation. The inside tube 5 is evacuated and sealed at its end, located at the outside of the hollow glass body 3, by means of the fused or welded carrier 6 of the anti-cathode which is to be made of a good heat conducting material (copper or the like). At the other end of this tube 5 which is located approximately in the center of the hollow glass body 3 is installed a circular diaphragm 7 with an opening 8 of a small diameter (only a few millimeters) which consists of a material which is hard to fuse and not easily penetrated by X-rays (tungsten, tantalum, etc.). In the hollow chamber of the double-walled pipe 4, 5 is installed a cylindrical intermediate wall 9 consisting of a material not easily penetrated by X-rays (lead etc.). This intermediate wall 9 is provided with an opening 10 for the exit of the useful X-rays which is at the same height as the reflector 11 (target) or the anti-cathode 11 at the outside of

the hollow glass body 3. The intermediate wall 9 has another opening 12 to allow cooling liquid to enter through the inlet conduit 13. This cooling medium occupies the hollow space inside the double-walled pipe 4, 5 which is not taken up by the intermediate wall 9 and flows through the outlet conduit 14.

By this arrangement the secondary electrons emanating from the focal spot are unable to impinge upon and cause radiation from the stem or body of the target or to cause an undesired and harmful charge on the glass walls, since these electrons are neutralized by the tubes 4, 5, 9 and by the diaphragm 7. Furthermore, since the reflector of the anti-cathode is separated from the cooling medium only by a metal wall of negligible thickness, the heat generated at the focal spot is easily conducted away. The parts necessary for the cooling arrangement of the X-ray tube, due to the fact that they are located on the outside of the hollow glass body, are easily accessible, even more so when the anode is kept at ground potential.

The X-rays possibly passing through the opening 8 are collected by properly designed parts of the cathode arrangement as, for instance, the focusing device 15 which is impenetrable to X-rays at least at the point where these last impinge.

Since it is important for a successful operation of the novel X-ray tube to have the cathode rays emanating from the glow cathode 16 pass through the opening 8 and being directed to the center of the reflector of the anti-cathode 11 it is advantageous to provide at the anode support or, according to the figure, in the cathode support 17, a flexible metal tube 18 as an intermediate part which, in a given case, may be corrugated in order to accomplish that, when the X-ray tube is manufactured, a corresponding adjustment may be made at the cathode 16 determining the direction of the cathode rays.

To accomplish an effective cooling of the anti-cathode and all adjacent metal parts it is possible to construct the tube as shown in the embodiment of Fig. 2, viz., in such a way that the intermediate wall 9, opaque to X-rays, is cut off at a certain distance from the anti-cathode and that, in an overlapping manner, the outside wall of the double-walled chamber is made opaque to X-rays which can be done, for instance, by covering it with a layer 19 opaque to X-rays. This arrangement has the advantage that all the space in the vicinity of the anti-cathode, inside the chamber

between the two walls may be occupied by the cooling medium.

If, as shown in the embodiments according to Figs. 1 and 2, the place of exit for the useful X-rays is located at the outside of the hollow glass body of the X-ray tube, the new X-ray tube presents the possibility of an especially simple construction and arrangement of protective means against coming in contact with its parts carrying high voltage. For this purpose there may be fastened, as schematically shown in Fig. 3, on a larger scale than the scale of Figs. 1 and 2, any device which may assume any shape which in itself is known to protect against high voltage. The protective device 20 may be designed, for instance, in case the anti-cathode is grounded, so as to have the shape of a closed tube of conducting material. Under certain conditions of operation, it may be desirable to omit the water-jacket and accordingly, in Fig. 3, there is provided a seal between the reentrant portion 21 of the glass envelope and the sealing ring 1 which is formed directly on the pipe 5. Although the water-cooling arrangement for the tube 5 has been omitted only in Fig. 3 which illustrates also an external shield for the X-ray tube, I wish it to be understood that it may be omitted when such a shield is absent as in the forms illustrated in Figs. 1 and 2.

30 What I claim as new and desire to secure by Letters Patent of the United States, is:

1. An X-ray device comprising an evacuated envelope which contains an electron-emitting cathode and comprising an anode, means for focusing a discharge upon a spot of restricted area on the anode, means, in addition to the focusing means, and forming a part of the envelope for restraining the discharge from impinging on the anode other than on the said spot of restricted area whereby secondary radiation is pre-

cluded, said discharge restraining means comprising a hollow cylinder terminating at one end in the anode and at the end nearer the cathode in a metal plate provided with a relatively small opening for the discharge.

2. An X-ray device comprising an evacuated envelope containing an electron-emitting cathode and an anode, means for focusing a discharge upon a spot of restricted area on the anode, means in addition to the focusing means and forming part of the envelope for restraining the discharge from impinging on the anode other than on the said spot of restricted area whereby secondary radiation is precluded, said discharge restraining means consisting of a member of 15 closed perimeter surrounding the anode and electrically connected thereto and containing material opaque to X-rays, said member comprising a hollow double-walled metal envelope extending toward the cathode and provided at the cathode 20 end with a restricted discharge opening.

3. An X-ray device comprising an evacuated envelope containing an electron-emitting cathode and an anode, means for focusing a discharge upon a spot of restricted area on the anode, 25 means in addition to the focusing means and forming part of the envelope for restraining the discharge from impinging on the anode other than on the said spot of restricted area whereby secondary radiation is precluded, a protective 30 shield surrounding the envelope, said discharge restraining means comprising a hollow cylinder terminated at one end by the anode and at the other end by a metal member provided with a discharge opening, the anode end of said cylinder 35 extending beyond said shield whereby the X-rays emitted by the anode are unobstructed by the shield.
